UNITED STATES PATENT OFFICE.

ELIZABETH FERGUSON HUME, OF DUNEDIN, NEW ZEALAND.

CORSET.

1,030,585.

Specification of Letters Patent. Patented June 25, 1912.

Application filed May 20, 1910. Serial No. 562,420.

To all whom it may concern:

Be it known that I, ELIZABETH FERGUSON HUME, a subject of Great Britain, residing at 70 Heriot Row, Dunedin, in the Dominion of New Zealand, have invented new and useful Improvements in Corsets, of which the following is a specification.

This invention relates to an improvement in corsets.

10 The object of the invention resides in the provision of flush busk clasps and a flush skirt band retainer.

In the drawings accompanying this specification: Figure 1 is a front view of the busk showing the two parts coupled, and indicating the skirt band retainer. Fig. 15 2 is a side elevation of the busk. Fig. 3 is a cross section of the busk through a fastener. Fig. 4 is a cross section through 20 the skirt band retainer.

The busks 23 and 24 are provided for each front section, having fastenings 25, 26 and 27 adapted to hold the busks together. Each of the fastening members on 25 busk 23 comprises a projecting piece 28 about one half of the thickness of the main portion, having a hole 29 punched therein, which hole is adapted to engage with a fastening member 30 formed in a recess 30 31 formed in the opposing busk 24. The said part 31 is made slightly bigger than the first mentioned projecting piece 28 so

that when the busks are clasped the surface is preferably smooth and flush.

The object of having the fasteners flush 35 is to prevent any undue wear on a dress front and to do away with unsightly projections caused by ordinary fasteners.

A skirt band retaining piece 32 is formed on one of the busks at any convenient place, 40 being preferably a continuation of one of the projecting pieces 28 of the busk which forms the fastener. The retaining piece is integral with the busk and preferably flush with the surface thereof. The portions of 45 the busks in line with the retaining piece are beveled toward the front edge to form a clearance between the busk and the retaining piece to enable a skirt band or belt to pass freely under the retaining piece. 50

Having described the invention, what I claim as new and desire to secure by Letters Patent is:—

A corset busk having fasteners thereon said busk being provided with a skirt band 55 retainer, the surface of said retainer being flush with the surface of the busk.

In testimony whereof I have signed my name to this specification in the presence of two subscribing witnesses.

ELIZABETH FERGUSON HUME.
